15 Claims. (Cl. 159—16)

This invention relates to methods and apparatus for evaporating liquids, and more particularly to the evaporation of water or other liquids from solutions by the utilization of heat that would normally be wasted.

In a great number of industries it is of great economical importance to be able to evaporate liquids, especially water, with the expenditure of as small a quantity of heat as possible. To this end, some evaporating systems have made use of apparatus of the multiple effect type, while other systems have used a so-called heat pump for compressing exhaust steam which is then utilized as the heating medium for evaporating purposes.

It is one of the objects of the present invention to provide a novel method and apparatus for evaporating liquids wherein the evaporation is accomplished in a plurality of stages each of which operates under substantially the same pressure both inside and outside of the apparatus and which utilize as the heating medium exhaust steam, flue gases and like sources of what is normally considered as waste heat.

Another object is to provide a method and apparatus of improved character for evaporating liquids wherein heat is transferred from a condensable gas-vapor mixture through a partition to a layer of the liquid or solution to be evaporated flowing on the opposite side thereof, while at the same time heat is transferred by evaporation from the liquid or solution to a heat absorbing medium including a non-condensable gas which is flowing in direct contact with, and preferably countercurrent to, the surface of the liquid layer.

A further object is to provide a novel evaporating system of this general character wherein the gas-vapor mixture constituting the heat absorbing medium in one stage is utilized as the heat yielding medium in another stage, and is even susceptible of subsequent repeated usage as the heat absorbing and heat yielding medium, alternatively,

These and other objects will appear more fully from a consideration of the detailed description of the invention that follows. Although a number of different mechanical embodiments of apparatus for carrying out the present invention are described and illustrated in the accompanying drawings, it is to be expressly understood that these drawings are for purposes of illustration only and are not to be construed as defining the scope of the invention, reference being had to the appended claims for the latter purpose.

In the drawings:

Fig. 1 is a diagrammatic illustration of one form of apparatus embodying the structural features, and capable of carrying out the method, of the present invention;

Figs. 2a and 2b are diagrams illustrative of the character and efficiency of the heat transmission from the condensable gas-vapor mixture to the liquid to be evaporated;

Fig. 3 is another diagrammatic illustration of a multi-stage evaporating system embodying the present invention;

Figs. 4, 5, 6, 7 and 10 illustrate various other forms of apparatus embodying the invention; and

Figs. 8a, 8b, 9a, 9b and 9c illustrate various means which may be employed for effecting thorough mixing of the heat absorbing medium and well-spread distribution of the flowing liquid to be evaporated.

The principle of the present invention is illustrated diagrammatically in Fig. 1, wherein there is disclosed an evaporating system of two stages employing heat exchangers A and B, each of which comprises a heating chamber and an evaporating chamber separated by a heat transmitting wall. In the first stage or exchanger A, a heating medium comprising a mixture of a permanent gas, such as air, and a condensable vapor, preferably at atmospheric pressure, is introduced at a into the heating chamber b and flows therethrough in heat yielding relation with the wall c thereof, the condensate and uncondensed portion of the gas-vapor mixture escaping at c. From the chamber b, heat is transferred into the liquid or solution to be evaporated which is contained in the vessel d constituting an evaporating chamber. Air or some other suitable permanent gas, preferably at atmospheric pressure, is then conducted over the surface of the solution in evaporating chamber d, said gas being introduced at e. During the direct contact flow of air and solution, heat is absorbed by the air from the solution in vessel d and water or other liquid is thereby evaporated from the surface thereof without boiling. In order to bring about rapid evaporation, the contact surface between the air and solution should be large, while in order that the air above the solution may become as nearly saturated as possible, the path of the air over the surface of the solution should be relatively long and the thickness of its layer should be relatively small.

The air escaping from the first exchanger A, which is saturated or approximately saturated with the vapor of the evaporated liquid, is then introduced through the pipe f into the heating

chamber *g* of the second stage or exchanger *B* and is there utilized as the heating medium, a portion of its vapor being condensed and giving up its heat to the solution in the vessel or evaporating chamber *h*, said solution having, of course, a lower temperature than the air-vapor mixture present in heating chamber *g*. Condensate and air saturated with vapor escape from heating chamber *g* at *l*, the temperature of the air-vapor mixture being lower at *l* than it is at *j*. Air is also introduced to evaporating chamber *h* at *i*, this air being conducted over the surface of the solution therein so as to cause vapor to be absorbed by the air in a manner similar to the evaporation in the first exchanger *A*. Air and absorbed vapor escape from evaporating chamber *h* at *k*, and, if desired, this air-vapor mixture may be used as the heating medium in the heating chamber of a third exchanger, and so on. The air introduced at *i* must have such a temperature and such a degree of saturation, and must be introduced in such quantity, that the temperature of the solution in evaporating chamber *h* will always be lower than that of the heat yielding air-vapor mixture flowing through heating chamber *g*.

The solution to be concentrated by evaporation is supplied at certain temperatures to evaporating chambers *d* and *h*, respectively, and is conducted therefrom through any suitable means such that a suitable liquid level and a desired concentration are maintained and obtained. The method and apparatus described is obviously applicable to any solution and any solvent. Likewise, any suitable gas or gas mixture, such as nitrogen, carbon dioxide, etc., may be introduced at *e* and *i* as the heat absorbing medium instead of air. It is also possible to employ either horizontal, vertical or inclined heat transmitting walls between the heating and evaporating chambers.

Decisive of the technical importance of the method of the present invention is the high degree of heat transmission obtained from the air-vapor mixture at condensation and through a metal wall to the streaming liquid solution to be evaporated. This is illustrated in Figs. 2a and 2b. The drop in temperature from vapor saturated air *a₆*, through a wall *b₆* to a flowing liquid *c₆* is shown diagrammatically in Fig. 2a. The quantity of heat which is transferred in such a system for each square meter of wall surface during a period of one hour and at a temperature difference of 1° C. between *a₆* and *c₆* has been determined experimentally for water, and the values of the coefficient of heat transmission so obtained are shown as ordinates on the diagram of Fig. 2b, the abscissae of said diagram representing the temperature in degrees centigrade of the condensable air-vapor mixture. Thus, the diagram of Fig. 2b represents the coefficient of heat transmission measured in kg. cal./m², 1° hour as a function of the temperature of the condensable air-vapor mixture. This curve will be displaced somewhat with changes in the velocities of the air-vapor mixture and the water, but the values in Fig. 2b refer to normal velocities of the order of 5 meters per second. It is apparent from the curve in Fig. 2b that this coefficient of heat transmission is very great.

As has previously been stated, in evaporating systems of the character described the air or gas constituting the heat absorbing medium flowing through the evaporating chamber must be of such a temperature and such a degree of satu-

ration that the temperature of the liquid solution being evaporated will always be lower than that of the condensable air-vapor mixture in the heating chamber from which the said solution is continually extracting heat. Such heat exchange obviously can take place only when the temperature of the liquid solution is at every point lower than the temperature of the gas-vapor mixture passing on the opposite side of the heat transmitting wall dividing the heating and evaporating chambers, since the gas-vapor mixture must be continually undergoing condensation. However, at the same time that the liquid solution is absorbing heat indirectly from the condensable gas-vapor heating medium, its temperature is also being lowered by evaporation from its surface over which is being flowed a current of unsaturated air or gas which, by absorption of heat and vapor from the liquid solution, gradually approaches saturation.

In order that evaporation accompanied by simultaneous cooling of the liquid layer may occur at each point on the surface of the liquid solution, it is necessary that the total heat content of the heat absorbing air or gas mixture passing over the solution be lower than the total heat content that would exist if said mixture were saturated at the temperature of the liquid solution with which it is in contact. Consequently, since the condition for existence of a heat transfer from the heat yielding medium to the liquid solution at the same point of the wall is that the temperature of the solution be lower than that of the heat yielding medium, it will be evident that, in order for the method of the present invention to be most efficiently carried out, the total heat content of the heat absorbing medium must be lower than that of the heat yielding medium. In other words, unless at every point the total heat content of the condensable gas-vapor heat yielding medium is greater than the total heat content of the heat absorbing air or gas plus its contained vapor, evaporation without boiling and accompanied by cooling of the liquid solution being evaporated will not be effectively obtained.

Fig. 3 illustrates diagrammatically a method and apparatus for effecting evaporation according to the present invention in four stages or heat exchange units connected in series, it being assumed that air is the permanent gas which circulates in the system. The four stages or heat exchange units are designated by I, II, III and IV, the temperatures being lowest in unit I and highest in unit IV. The solution to be evaporated is injected into evaporating chambers *c₁*, *c₂*, *c₃* and *c₄* at *a₁*, *a₂*, *a₃* and *a₄*, respectively, having been preheated to different temperatures, the lowest temperature prevailing at *a₁* and the highest at *a₄*. The solution is injected upon the heating surfaces in any suitable manner such that the latter are entirely covered by a layer of flowing liquid, the unevaporated portion of which, upon reaching the bottoms of the units in question, is conducted off at *b₁*, *b₂*, *b₃* and *b₄*, respectively. If desired, the unevaporated portions of the solution may be recirculated and pumped (if preferred, with the addition of heat) either to *a₁*, *a₂*, *a₃* or *a₄*, respectively (in other words, returned to the same units), or to other units in the system, as for example from *b₂* to *a₁*.

By means of a fan or compressor *A₁* unsaturated air of relatively low temperature is sucked through the channel *H* into the evaporating chamber *c₁* of heat exchange unit I, wherein the

air will flow upwardly countercurrent to the solution and absorb vapor therefrom, the degree of saturation of the air thereby being progressively increased accompanied by a transfer of heat from 5 and a corresponding progressive decrease in temperature of the solution. From the top of chamber c_1 the mixture of air and its absorbed vapor is conducted through the pipe d_1 to the evaporating chamber c_2 of unit II wherein it is conducted 10 over the surface of a flowing solution of a temperature higher than that of the solution in chamber c_1 . Therefore, in chamber c_2 the saturation temperature of the air will be increased and it will absorb a further quantity of vapor. 15 Leaving chamber c_2 the air is conducted through the pipe d_2 to the evaporating chamber c_3 of unit III, wherein the temperature is higher than in c_2 and again results in additional absorption of vapor by the air from the solution, and thence 20 through the pipe d_3 to the evaporating chamber c_4 of unit IV where a still higher temperature prevails and a still further quantity of vapor is absorbed. 25 After leaving the unit IV, the mixture of air and its absorbed vapor is conducted through the pipe d_4 to a heating apparatus C_1 wherein it may be heated by means of a suitable steam coil M and supplied with additional water or solution injected through a pipe B_1 . Thus the air will be 30 completely saturated with vapor, and the air-vapor mixture raised to a higher temperature than before. It is also possible to introduce steam directly from any suitable steam generator (not shown) into the air-vapor mixture in apparatus 35 C_1 . The air should, however, when leaving apparatus C_1 , be completely saturated and of a temperature which is higher than that of the liquid solution which is supplied to evaporating chamber c_4 . 40 The hot saturated air is conducted from the apparatus C_1 through pipe g_4 to the heating chamber e_4 of stage or unit IV. By reason of the fact that the air-vapor mixture entering the chamber e_4 is of a higher temperature than the liquid entering at a_4 , condensation of some of the vapor takes place in the chamber e_4 and the heat of condensation is transferred through the wall of said chamber to the flowing liquid solution in evaporating chamber c_4 , which quantity 45 of heat is in turn consumed in the formation of vapor and its absorption by the air in c_4 . The water of condensation obtained in the chamber e_4 is collected at the bottom thereof and discharged therefrom at f_4 . From the chamber e_4 the condensable air-vapor mixture is conducted through 50 the pipe g_3 to the heating chamber e_3 of unit III. Inasmuch as the temperature of the solution entering at a_3 is lower than that of the solution entering at a_4 , the air-vapor mixture supplied 55 to the chamber e_3 will have a higher temperature than the solution in the chamber c_3 , a condition which causes heat to be transferred from e_3 to c_3 , evaporation to occur in c_3 , and condensation to occur in e_3 , the water of condensation being collected at the bottom and conducted off through pipe f_3 . Similarly, the temperature in the heating chamber e_2 will be higher than in the evaporating chamber c_2 , and higher in chamber e_1 60 than in chamber c_1 , which results in heat being transferred from e_2 to c_2 and from e_1 to c_1 , additional evaporation in c_2 and c_1 , and additional condensation in e_2 and e_1 . The condensate from e_2 is conducted off at f_2 , while the condensate 65 from the chamber e_1 is discharged at f_1 . 70 The air and any remaining uncondensed vapor leaving the chamber e_1 is conducted through the pipe g_1 to the condenser D , wherein the air is cooled by direct or indirect cooling. The condensate, or with direct cooling, both the condensate and the cooling water, escapes through the liquid-sealed pipe E . The cooled and relatively dry air is then conducted through H back to the evaporating chamber c_1 of unit I, and again circulated through the evaporating chambers c_1 , c_2 , c_3 and c_4 and through the heating apparatus C_1 10 by the fan A_1 , and then back through the heating chambers e_4 , e_3 , e_2 and e_1 , and so on. The heating in apparatus C_1 and the subsequent cooling in chamber D are useful steps in the prevention of heat stabilization within the system. 15 Through the liquid seal F fresh air is sucked into the system automatically in case the pressure in the apparatus should sink below atmospheric, while through the liquid seal E air is automatically blown out in case the pressure 20 should rise above atmospheric. These two liquid seals may be made adjustable, whereby the pressure in the apparatus may be kept approximately equal to the atmospheric pressure. Although it is obvious that a small difference in 25 pressure must exist on the opposite sides of fan A_1 in order that the air and air-vapor mixture may be circulated through the system, this pressure difference need never exceed approximately 200 mm. of water column. It may therefore be 30 considered, for all practical purposes, that the present system operates at substantially atmospheric pressure. 35 Instead of water, a solution may be added through pipe B_1 in heating apparatus C_1 , and 40 concentration of this solution then obtained by vaporization in C_1 due to the heating effect of coil M . The unevaporated water or concentrated solution will flow out of the heating apparatus C_1 through liquid seal G . 45 By operating the method and apparatus of the present invention at substantially the same pressure interiorly and exteriorly, the problems hitherto presented to the art of preventing leakage, providing heavy or strong construction to 50 resist pressure differences, providing vacuum pumps of sufficient capacity, etc., are avoided. 55 The method of the invention is also such as to assure against operating conditions that are likely to produce precipitation or incrustation 60 on the heat transmitting wall either from the liquid being concentrated or from the gas used as the heating medium, if they should contain ingredients likely to form scale. In the present method, evaporation is effected without the production of boiling within the liquid being concentrated, and there is therefore no danger that the flowing layer of liquid will become so thin, or its concentration so great, because of localized heat conditions, that precipitation or incrustation 65 will ensue. Since the system operates at atmospheric pressure and without boiling, the temperature within the apparatus is always less than 100° C. Actually, under preferred operating conditions, this temperature seldom exceeds 70 a maximum of 85° C. Since the highest temperature obviously prevails at the point from which the heat is initially transferred, that is to say in the condensable gas-vapor mixture, it is obvious that the liquid solution which is evaporating 75 will not be subjected to a temperature even as high as 85° C., the result being that incrustation on the heat transmitting surfaces during treatment of those liquids which tend to form scale is reduced to a minimum. 75

These incrustations will not only occur on the solution side of the heat transmitting wall but also on the heating side, provided that the heating medium is such as to possess a scale forming tendency. For example, if flue-gases are used as the heating medium, it is necessary to keep the temperature of the flue-gases as low as possible so that the incrusting constituents will not be permitted to precipitate. The solubility of such constituents decreases with an increase of temperature, which fact is also conducive to the use of a condensable heat yielding medium. Not only are proper temperatures thus maintained in the heat yielding medium so as to avoid precipitation and incrustation, but the formation and presence of the condensate also tends to wash the walls and remove any scale that might tend to form thereon.

Moreover, since in the present method vapor is generated from the surface of the liquid solution due to the direct contact therewith of the permanent gas flowing thereover, no boiling occurs within the solution and an increase in concentration of the solution along the heat transmitting wall is avoided, thereby obviating the occurrence of precipitations at that point. Since the increase in concentration occurs at the free surface of the solution, any precipitations that are formed will not stick to the wall but will be washed away by the unevaporated portion of the solution. This result is further assured by permitting the solution to flow over the heat transmitting surfaces in a sufficiently thick layer.

Since large quantities of solution flow through the apparatus, the difference in concentration between incoming and outgoing liquid will be small. Consequently, in order to obtain a desired final concentration, the liquid solution must be circulated in the apparatus, as above described. Circulation also promotes a uniform temperature distribution throughout the mass of the solution, so that local overheating thereof is avoided as far as possible. This is of special importance in connection with the evaporation of those solutions which contain substances that are sensitive to certain temperatures, such as wort solutions containing enzymes, ferments or the like, which as a rule do not withstand temperatures exceeding 50° C.

Circulation of the solution is also important in the obtaining of a gradual concentration. For example, in concentrating a lye solution, circulation of the solution is essential for the purpose of covering the heat transmitting wall with a layer of lye sufficiently thick to assure a substantially uniform heating thereof accompanied by a uniform cooling of the heat yielding medium. If the quantity of lye solution supplied is just enough to obtain the desired final concentration, it may happen, having regard to a practical size of apparatus, that this quantity will be too small to completely cover the heat transmitting wall, with the result that incrustation and uneconomical heat utilization will occur. On the other hand, if a sufficient quantity of lye solution is supplied, over-heating at any particular place will be avoided and substantially all of the available heat of the heat yielding medium will be absorbed. Since this will slow up the process of concentration to some extent, circulation of the lye solution is necessary.

In order to promote even temperature distribution throughout the liquid solution as far as possible during circulation, the heat transmitting

walls or surfaces are preferably formed as generally plane plates, this construction also being desirable because of its relatively low cost. For example, a suitable construction may comprise heat transmitting surfaces in the form of spaced plates, the solution in the evaporating chamber being permitted to flow over the surfaces of the two plates which separate this chamber from the adjacent heating chambers. Such a construction is shown in Fig. 4, wherein three evaporating chambers *c* are arranged to operate in parallel, that is, each chamber containing solution and air at the same temperatures as prevail in the other chambers. As shown, the evaporating chambers *c* and the heating chambers *e* are disposed alternately, all of the evaporating and heating chambers being preferably connected with common channels for the supply and escape of air, air-vapor mixture, solution and condensate, respectively.

If it is desired to maintain the vapor absorbing air as saturated as possible at the particular temperatures used, it is preferable that the air be caused to flow along a relatively long path over the surface of the solution. This result, which is particularly desirable in the stage of the system having the highest temperature, may be attained without increasing the height of the apparatus by causing the vapor absorbing air to flow through two or more evaporating chambers in series, which chambers, however, are supplied with solution of the same temperature and have their heating chambers operating in parallel. One embodiment of such an apparatus is illustrated in Fig. 5 wherein the heat yielding air-vapor mixture enters both heating chambers *e* at the same temperature and flows therethrough in parallel, whereas the air intended to absorb vapor from the solution flows first through evaporating chamber *c*₁ and then through chamber *c*₂.

If it is desired that the heat yielding air-vapor mixture be cooled down as far as possible, it is feasible to connect two or more heating chambers in series, the solution, or the evaporating air, or both, then being supplied at the same temperature (in parallel) to the corresponding evaporating chambers.

In Fig. 6 there is illustrated an evaporating system of two stages wherein both the heating chambers and the evaporating chambers are connected in series, but wherein the heat yielding air-vapor mixture in one heating chamber *e*₂ flows in the opposite direction, relative to the flow of solution, to that in which it flows in the second chamber *e*₁, the vapor absorbing air likewise flowing oppositely, relative to the flow of solution, in evaporating chamber *c*₁ to the direction in which it flows in chamber *c*₂. However, in each stage or unit, the heat yielding air-vapor mixture and the vapor absorbing air flow in directions opposite to one another. This flow on the countercurrent principle obviously may be continued through any desired number of heating chambers and evaporating chambers.

If common steam, for instance at a temperature of 100° C., is available, the evaporating system may preferably be arranged in such a manner that the stage or unit of highest temperature is heated with the aid of this steam. This is illustrated in Fig. 7 wherein steam is introduced into heating chamber *e*₄ through *s*, the water of condensation being drawn off at *f*₄. The vapor absorbing air escaping from the evaporating chamber *c*₄ may then be admixed with a suitable quantity of steam supplied through *s*₁, and, if

desired, spray water may be added thereto, whereupon the air-steam mixture may be conducted into a heating chamber of a lower temperature and there utilized as the heat yielding medium, and so on.

The need for heat for the evaporation may also be supplied by utilizing the heat content of gases which would otherwise be wasted, such as flue-gases, combustion-gases and the like. After these 10 gases have been saturated with vapor through direct contact with water or a solution, or by the introduction of steam into the gas, they may be passed through the heating chambers of the system in the manner previously described. If 15 desired, the gases leaving the heating chambers, or part of them, after having been cooled by direct or indirect cooling, may be returned through the evaporating chambers to serve as the vapor absorbing medium. It will be understood, however, 20 that where these gases are used for heating purposes only, fresh air or some other suitable vapor absorbing medium will be used for the evaporation. The gases or the air escaping from the last evaporating chamber may, upon saturation, 25 be used again as the heating medium in the same or some other evaporating system so long as said gases or air are introduced into an apparatus operating at a suitable temperature with respect to the temperature of the gas or air, as previously 30 explained.

Neither the vapor absorbing air nor the air-vapor mixture used for heating need necessarily flow through all of the units of the apparatus, but may in part be permitted to flow around one 35 or more units, particularly when it is desired to regulate the temperature of the apparatus. Likewise, fresh air, hot air, or the circulating air may, if desired, on having been cooled for condensation, be introduced into any stage of the apparatus. It is also obvious that air may be drawn off from the apparatus at any point, if desired. For instance, hot gases, such as flue-gases, may be introduced into the unit of lowest temperature, part of which gases are then removed from 45 the system before reaching the next unit.

In order to effect thorough mixing of the vapor absorbing air, the evaporating chambers may be provided with spaced rods *r* or baffle plates *p*, as shown in Figs. 8a and 8b, respectively, extending into the path of flow of the air so as to cause eddy currents therein. To effect uniform distribution of the flowing liquid or solution, so that the entire heat transmitting surfaces will be covered thereby, the walls or plates separating the 55 evaporating and heating chambers may be provided with wires *w*, wire netting, rods or the like, as indicated in Fig. 9a, or ridges or grooves may be pressed into said walls or plates, as shown in Figs. 9b and 9c, said ridges or grooves preferably being disposed horizontally.

The heat content of the condensate drawn off from the various units of the system may preferably be utilized by conducting the condensate through the various other units, from a higher 65 to a lower temperature, and by introducing the condensate into the heating chambers of said units in such a manner that it is further cooled with a consequent giving off of heat.

The method of the present invention may also 70 be employed in connection with evaporating devices of the type employing rotating heating surfaces, such as those employed for the evaporation of thick solutions, the drying of cellulose, etc. Fig. 10 illustrates diagrammatically an apparatus wherein the present method may be em-

ployed for the concentration of lye solutions. As shown, lye solution is circulated through vessels *c*₇ and *c*₈ each of which is positioned directly beneath a rotatable drum *D*₇ and *D*₈. The lowest portions of the peripheries of drums *D*₇ and *D*₈ dip into the lye solution as it flows through vessels *c*₇ and *c*₈ and carry some of the solution around with them during the rotation in the form of a thin film spread on the surface of the drums. Vapor absorbing air or gas is drawn in 10 through *d*₅ by fan *A*₁ and flows around the drum *D*₇ in the space between the periphery thereof and the outer casing which constitutes the evaporating chamber. During the flow of the vapor absorbing air or gas around the drum, during 15 which time the drum is also rotated, preferably in a direction opposite to the direction of flow of the vapor absorbing medium, heat is absorbed and evaporation takes place from the film of lye solution carried by the drum. The 20 vapor absorbing medium is then conducted through *d*₇ to the evaporating chamber surrounding drum *D*₈ wherein additional vapor is absorbed from the lye solution carried by drum *D*₈, said solution being at a higher temperature 25 than the solution in vessel *c*₇ with which drum *D*₇ is in contact.

The vapor absorbing air or gas is then led through *d*₈ to heating chamber *C*₁ wherein its 30 temperature is increased, as by heating coil *M*, and it is completely saturated at its increased 35 temperature by a spray of water or solution injected into chamber *C*₁ through *B*₁, as previously described. The saturated, highly heated air- or 40 gas-vapor mixture is then pumped by fan *A*₁ through *g*₁ into drum *D*₈, the interior of said 45 drum constituting a heating chamber *e*₈. In flowing through heating chamber *e*₈, the air- or 50 gas-vapor mixture acts as a heat yielding medium, some of the vapor being condensed and the 55 heat of condensation being transmitted through drum *D*₈ to the lye solution film carried thereby, this heat in turn being transmitted by evaporation to the heat absorbing air or gas flowing around the drum. After passing through 45 heating chamber *e*₈, the heat yielding medium is conducted through *g*₁ to the heating chamber *e*₇ within drum *D*₇ wherein still more heat is given up to the solution carried by said drum. Upon leaving heating chamber *e*₇ through *g*₂, 60 the heat yielding medium may, if desired, be supplied to still another stage or unit of lower temperature, or it may be cooled and dried and again circulated through the system as the vapor absorbing medium, as previously described in 65 connection with Fig. 3.

There is thus provided by the present invention a new and improved system for effecting evaporation from liquids or solutions which requires only structurally simple and inexpensive 70 apparatus and operates at a relatively high efficiency. The operating pressures in all stages of the system are substantially equal, and are preferably substantially the same as the atmospheric pressure, a feature which obviates many 75 of the difficulties hitherto experienced with evaporating systems requiring pressures both above and below atmospheric. The process of the present invention also makes possible the utilization, as a source of heat, of flue-gases and other mediums hitherto regarded as unsatisfactory for heating purposes. The present invention also provides for the efficient utilization of latent heat and produces increased heat transmission due to the reduction to a minimum of 80

incrustations on the surfaces of the heat transmitting walls both in the evaporating chamber and in the heating chamber.

While several different forms of apparatus and various modifications in the steps of the method have been described and diagrammatically illustrated in the accompanying drawings, it will be obvious that the apparatus of the invention is not limited to the forms shown in the drawings, but is capable of a variety of mechanical embodiments, and that the inventive concept of the method is likewise susceptible of embodiment in processes which vary in their details from those disclosed. Reference is therefore to be had to the appended claims for a definition of the limits of the invention.

This application is a substitute for my prior application, Serial No. 362,976, filed May 14, 1929.

What is claimed is:

1. A method of evaporating liquids under substantially the same pressure inside and outside of the apparatus, which includes indirectly transferring heat through an intervening partition to the liquid to be evaporated by conducting a heat yielding medium, comprising a mixture of gas which is non-condensing under the conditions of operation and a condensable vapor, along the opposite side of the partition from the liquid to be evaporated to progressively increase the temperature of said liquid and progressively decrease the temperature of said gas-vapor mixture, and passing a heat absorbing medium including a non-condensable gas in direct contact with the liquid to vaporize said liquid and form a gas-vapor mixture, while maintaining the relative temperatures of said heat yielding medium and said heat absorbing medium and said liquid such that at all points of contact between said liquid and said heat absorbing medium the total heat content of said heat absorbing medium is less than the total heat content which would exist if the gas-vapor mixture constituting said medium were saturated at the temperature of the liquid at said point.

2. A method according to claim 1 wherein the heating and evaporating steps are carried out simultaneously by flowing the heat yielding and heat absorbing media on opposite sides of the intervening partition and wherein the relative temperatures and degrees of saturation of the heat yielding medium and the heat absorbing medium are maintained such that at each point within the apparatus the total heat content of said heat absorbing medium is less than the total heat content of the heat yielding medium.

3. A method according to claim 1 wherein the evaporation is carried on at substantially atmospheric pressure.

4. A method according to claim 1 which includes the step of recirculating the liquid to be evaporated with respect to said partition.

5. A method according to claim 1 wherein the condensable vapor forming a part of the heat yielding medium is the vapor corresponding to the liquid to be evaporated.

6. A method according to claim 1 which includes the step of conducting the gas-vapor mixture constituting the heat absorbing medium at one stage as the heat yielding medium in heat yielding relation with the partition of a second stage.

7. A method according to claim 1 which includes the steps of conducting the gas-vapor mixture constituting the heat absorbing medium

at one stage as the heat yielding medium in heat yielding relation with the partition of a second stage and heating the gas-vapor mixture between its use as the heat absorbing medium and as the heat yielding medium.

8. A method according to claim 1 which includes the steps of conducting the gas-vapor mixture constituting the heat absorbing medium at one stage as the heat yielding medium in heat yielding relation with the partition of a second stage and adding vapor to the gas-vapor mixture between its use as the heat absorbing medium and the heat yielding medium.

9. A method according to claim 1 which includes the steps of conducting the gas-vapor mixture constituting the heat yielding medium at one stage as the heat absorbing medium in heat absorbing relation with the liquid of another stage and cooling the gas-vapor mixture between its use as the heat yielding medium and the heat absorbing medium.

10. A method according to claim 1 wherein the heating and evaporating steps are carried out simultaneously by flowing the heat yielding and heat absorbing media on opposite sides of the intervening partition and wherein the direction of flow of the heat yielding medium on one side of partition is opposite to the direction of flow of the heat absorbing medium on the opposite side of said partition.

11. An apparatus for evaporating liquids under substantially the same interior and exterior pressures including a plurality of heating chambers connected in parallel with one another, a corresponding number of evaporating chambers connected in series with one another, a heat transmitting wall in each of said heating chambers, means circulating the liquid to be evaporated over each of said heat transmitting walls, means circulating a heat yielding medium, comprising a mixture of gas which is non-condensing under the conditions of operation and a condensable vapor, through each of said heating chambers along the opposite side of said heat transmitting wall from said liquid and throughout the length of said wall to progressively increase the temperature of said liquid and progressively decrease the temperature of said heat yielding medium, and means for conducting a heat absorbing medium including a non-condensable gas through said evaporating chambers in series and over the surface of the liquid therein to progressively evaporate liquid from the free surface of said liquid.

12. An apparatus for evaporating liquids under substantially the same interior and exterior pressures including a plurality of heating chambers, a plurality of evaporating chambers, a heat transmitting wall in each heating chamber, means circulating the liquid to be evaporated over each heat transmitting wall, means circulating a heat yielding medium, comprising a mixture of gas which is non-condensing under the conditions of operation and a condensable vapor, through each heating chamber along the opposite side of the heat transmitting wall from said liquid and throughout the length of said wall to progressively increase the temperature of said liquid and progressively decrease the temperature of said heat yielding medium, means for conducting a heat absorbing medium including a non-condensable gas through said evaporating chambers over the surface of said liquid to progressively evaporate liquid from the free surface of said liquid, means for withdrawing the heat

absorbing medium with its contained vapors from said plurality of evaporating chambers and adding heat thereto and then returning the same as the heat yielding medium flowing through said heating chambers, and means for withdrawing said gas-vapor mixture from said plurality of heating chambers and withdrawing heat therefrom and then returning the same as the heat absorbing medium flowing through said evaporating chambers.

13. A method of evaporating liquids under substantially the same pressure inside and outside of the apparatus which includes indirectly transferring heat through an intervening partition to the liquid to be evaporated, said heat substantially consisting of evaporating heat of a heat yielding medium comprising a mixture of gas which is non-condensable under the conditions of operation and a condensing vapor, by conducting said heat yielding medium along the opposite side of the partition from the liquid to be evaporated to progressively increase the temperature of that liquid and progressively decrease the temperature of said gas vapor mixture, and conducting a heat absorbing medium including a non-condensable gas over the surface of the liquid and in a direction opposite to that in which

the heat yielding medium flows relative to the liquid to vaporize said liquid from the free surface thereof and form a gas vapor mixture, while maintaining the relative temperatures of said heat yielding medium and said heat absorbing medium and said liquid such that at all points of contact between said liquid and said heat absorbing medium the total heat content of said heat absorbing medium is less than the total heat content which would exist if said gas vapor mixture were saturated at the temperature of the liquid at said point, and recirculating the liquid to be evaporated with respect to said partition.

14. A method according to claim 13 which includes the step of conducting the heat yielding medium at one stage as the heat absorbing medium in direct contact with the liquid in a second stage.

15. A method according to claim 13, which includes the step of conducting the heat yielding medium at one stage as the heat absorbing medium in direct contact with the liquid in a second stage and cooling the heat yielding medium before its use as the heat absorbing medium.
